No. 809,961.

PATENTED JAN. 16, 1906.

J. P. LANCASTER.

RAILWAY TIE.

APPLICATION FILED APR. 27, 1905.

UNITED STATES PATENT OFFICE.

JOHN P. LANCASTER, OF CINCINNATI, OHIO, ASSIGNOR OF ONE-FOURTH
TO WILLIAM M. FRIDMAN, OF CINCINNATI, OHIO.

RAILWAY-TIE.

No. 809,961.

Specification of Letters Patent.

Patented Jan. 16, 1906.

Application filed April 27, 1905. Serial No. 257,703.

To all whom it may concern:

Be it known that I, JOHN P. LANCASTER, a citizen of the United States, residing at Cincinnati, in the county of Hamilton and State 5 of Ohio, have invented new and useful Improvements in Railway-Ties, of which the following is a specification.

My invention relates to improvements in railway-ties.

Objects of the invention are principally to provide for effectiveness in the retention of the rails in place and yet permit the retaining means therefor to readily conform to the movement of the parts under the stress or weight 15 of passing trains.

Said invention consists of certain structural features, substantially as hereinafter fully disclosed and particularly pointed out.

In the accompanying drawings, illustrating 20 the preferred embodiment of my invention, Figure 1 is a cross-section of a railway with said invention applied thereto. Fig. 2 is a detailed broken sectional view produced upon the line $\alpha\alpha$ indicated upon Fig. 1. Fig. 3 is 25 a perspective view of one of the separated rail-base clamp members. Fig. 4 is a like view of a companion clamp member. Fig. 5 is a detached perspective view of one of the clamp-member locking devices or bars.

In the disclosure of my invention I provide 30 a suitable tie-bar member 1 and employ in connection therewith resilient chair members 2, said tie member and chair member being practically of the same general outline as heretofore adopted. As well understood, the 35 tie-bar member 1 is designed to support the usual rails, the resilient bracing-chair members 2 having upraised portions or elevations 2^a, forming practically chairs and resting 40 against the lower side of said tie-bar directly under the rails to receive the pressure exerted upon the latter, and which have a bracing action upon the tie-bar. The resiliency of the chair member permits the requisite yielding or flexing action incident to traffic over the 45 rails, as will be appreciated. The chair members 2 have extending from opposite sides of their elevations or upraised portions 2^a, upward-inclined continuations thereof 2^b these latter themselves being extended into horizontal or right-lined portions 2^c, resting flat against the under side of the tie-bar member 1, and through the portions 2^c and the latter

are passed or inserted bolts 3, thus securing the chair members to said tie members. The 55 tie and chair members are all ballasted by suitably embedding the same in the road-bed or foundation.

Two complementary clamp members 4 4^a are provided, one for each side of each rail, 60 with their inner end portions 4^b 4^c, respectively, effective to engage or bear upon the base-flanges of the rails and having their main or body portions 4^d 4^e, respectively, adapted to be arranged below the tie member, 65 being provided intermediately of their thus-formed upper and lower portions with contracted or neck portions 4^f 4^g, respectively, which are received within openings 1^b 1^a in the tie member 1. Each of these neck or 70 contracted portions 4^f 4^g has a notch 4^h therein to receive one of the edges of each of the holes or openings 1^a 1^b. The body or main portions of the clamp members 4 4^a are provided each upon its upper edge with a preferably rounded projection or elevation 4^k, forming a bearing or fulcrum therefor upon the under side of the tie member 1, thus constituting said clamp members or levers, their lower free ends being beveled or inclined, as 80 at 4^l 4^l, and resting or bearing at those points upon the inclined surfaces 2^b of the chair members 2. From this it will be noted that as the rails, together with the tie-bars and the chair members at these points, are borne 85 down under the weight of a passing train, while the inclined portions 2^b of said chair members remain relatively stationary to the clamp or lever members 4, the latter will pivot or fulcrum, as aforesaid, and thus move with 90 or retain their firm clamping action upon the rail-flanges, the tendency being to intensify or increase this impinging or clamping action. The relatively outer end portions 4^m 4ⁿ of the clamp members 4 4^a are effective, 95 one to bind upon the corresponding edge of the wall of the opening 1^b in the tie member 1, while the other is considerably elongated or extended to enable it to span or overlie the opening or slot 1^a in said tie member and rest 100 upon the latter, the purpose of which is obvious.

An interlocking bar or fork 5 is applied to the lever or clamp member 4 of each rail, with its outer end portion longitudinally slotted, as at 5^a, to receive the chair-member-fas-

tening bolt 3, for securing that end of said fork or bar in place. Said bar or fork has its opposite end portion reversely curved or carried generally downward and also longitudinally slotted, thus providing prongs or fingers 5^b, adapted to pass down through the opening 1^b, astride of the clamp member 4, and extend under the tie member 1, and by thus embracing the lever or clamp member 4 and by taking up all lateral play or movement which the latter would otherwise have said clamp member or lever is rendered effective to accordingly hold the rails against any possible lateral displacement, as is apparent.

I claim—

1. A railway-tie member, a chair member adapted to be housed within said tie member, clamp members or levers, adapted to bear upon the under side of said tie member and to engage the rail base-flanges and a locking member effective to stride one of said clamp members and to interlock therewith and with said tie member and the base-flange of a rail.
2. A railway-tie member, a chair member adapted to be housed within said tie member, clamp members or levers adapted to bear upon the under side of said tie member and to engage the rail base-flanges, and a locking member effective to stride one of said clamp members and having a reversely-curved end portion adapted to extend down through an opening in said tie member and in under the

latter, and means for securing the opposite end of said locking member in place.

3. A railway-tie member, a chair member adapted to be housed within said tie member, clamp members or levers adapted to bear upon the under side of said tie member and to engage the rail base-flanges, and a locking member having a slotted reversely-curved end portion, effective to stride one of said clamp members and to extend down through an opening in said tie member and means for securing the opposite end of said locking member in place.

4. A railway-tie member, a chair member adapted to be housed within said tie member, clamp members or levers adapted to bear upon the under side of said tie member and to engage the rail base-flanges, and a locking member having a reversely-curved bifurcated or forked end portion effective to stride one of said clamp members and to extend down through an opening in said tie member and in under the latter, said locking-bar having its opposite end portion provided with a slot to receive, and provide for the securing thereof in place upon the tie member.

In testimony whereof I affix my signature in presence of two subscribing witnesses.

JOHN P. LANCASTER.
